Specification of Letters Patent. Patented Mar. 2, 1915.

Application filed August 14, 1913. Serial No. 784,778.

To all whom it may concern:

Be it known that I, JOHN STODDARD, a citizen of the United States of America, and resident of Wilmington, Delaware, have invented a new and useful Improvement in 5 Bearings, which improvement is fully set forth in the following specification.

This invention relates to improved bearings designed especially for application to 10 the table rolls which support the making-wire of the shaking-section in a Fourdrinier paper-making machine, such bearing will also be found useful for other rolls at other locations in paper-making machinery.

15 As is well known, the shaking-section of a Fourdrinier machine includes in its structure two parallel side supporting rails or table bars adapted to be rapidly vibrated horizontally at their forward ends about 20 pivots at their rear ends; and also includes a succession of closely spaced horizontal table-rolls upon which the making-wire rests in its advance through the shaking-section of the machine. The making-wire is also 25 laterally vibrated or shaken with the shaking-section, and by its frictional contact with and pull upon the table-rolls rotates the latter in bearings at opposite ends thereof, said bearings being mounted upon or supported from the side rails, the rolls spanning 30 the space between said rails. To obtain maximum efficiency in operation and to minimize the strain and wear upon the making-wire, it is necessary to accurately adjust 35 each table-roll to uniformly position the series of rolls to the making-wire, and to make readjustment from time to time to compensate for wear upon the bearings. Adjustable bearings have heretofore been 40 devised for this purpose.

One of the principal objects of the present invention is to improve upon such bearings, to afford greater durability and rigidity of structure, ease and accuracy of adjustment, 45 and to impose the wear upon relatively inexpensive and easily replaced parts of the bearing rather than upon the side rails or other parts of the structure which can only be replaced at considerable expense.

50 A further object is to provide a bearing having in conjunction therewith a passage leading therethrough to the opposing surfaces of the axle of the roll and the bearing, and means for supplying through such pas-

sage a liquid or semi-liquid which by its 55 action will serve to reduce the friction between said opposing surfaces.

These and other objects are attained by the structure of this invention, a now preferred embodiment of which is illustrated in 60 the accompanying drawings, wherein—

Figure 1 is a fragmentary top plan view of a portion of a side-rail of the shaking-section of a paper-making machine and three of a series of table-rolls associated therewith; Fig. 2 is a vertical sectional view through one of the table-roll bearings; Fig. 3 is a detail end view of said bearing; Fig. 4 is a transverse section on line 4—4 of Fig. 1; and Fig. 5 is an elevation from the right of 70 Fig. 4, showing (in place of the grease cups of Figs. 2 and 4) pipe connections to the bearings for supplying thereto liquid under pressure.

The side-rail shown in the drawing includes in its structure the bar 6 with depending brackets 7 supporting an angle bar 8.

9 are table-rolls, of which only three are shown in the drawing, each having at opposite ends thereof projecting axles 10. Each 80 projecting axle 10 rests in a trough-like bearing surface member 11 having thereon a vertically depending stem 12 fitting within a hollow adjustable screw-threaded sleeve socket or tubular member 13, a shoulder 14 85 about the upper end of said stem resting against the upper edge of said screw. The screw 13 makes screw-threaded engagement with an opening through the horizontal lip of the angle bar 8 and carries a lock-nut 15. 90 For longitudinally adjusting each roll 9 and restricting the endwise play thereof in the vibration of the shaking section, there is opposed to the end of each axle 10 a set-screw 16 threaded horizontally through an 95 opening in the upright lip or flange of the angle bar 8 and carrying a lock-nut 17.

As will be obvious, to vertically adjust a roll, the lock-nut 15 of its bearing is first loosened and the hollow screw-threaded 100 member 13 then rotated by any suitable implement, such as a screw-driver engaging the kerfs 18 at the outer end of the screw. The upper end of the screw rotating against the shoulder 14 of the bearing element 11 105 lifts the latter and with it the axle 10 and roll 9. When the desired position has been attained, the lock-nut 15 is again tightened.

In the lateral movement of the shake-frame, during which the side-rail turns slightly on the pivot at its rear end, the stem 12 of the bearing element 11 turns slightly in the hollow screw-threaded member 13. The vibratory movement of the shake-frame gives an endwise movement to the rolls 9 carried thereby, imposing a corresponding strain and wear upon their bearings. In the bearing of this invention, such wear falls upon the opposing surfaces of the stem 12 and screw 13 tending to wear the opening through the screw to an oblong shape. But the occasional turning of the screw 13 in adjusting the bearing relatively changes the position of the opposing surfaces of the stem 12 and interior of the screw, thereby presenting a fresh surface of the screw to the wear resulting from the endwise movement of the rolls. When, however, the wear thus imposed upon the screw 13 renders the latter defective for its purpose, it is replaced by a fresh screw at small expense. With the lock-nut 15 seated tightly against the angle bar 8, there will be practically no wear imposed upon the opening through said bar, as has been experienced in other structures in which such wear has necessitated replacing side-bars at considerable expense. As clearly illustrated in Figs. 2 and 3, the bottom of the trough-like bearing surface of the member 11 is grooved longitudinally at 19, such groove being of greatest depth and dimensions at its middle and tapering up to the normal surface at its opposite ends. A small passage 20 leads from the deepest portion of the groove 19 axially through the stem 12. A tubular plug or connection 21, extending upwardly through the lower end of the hollow screw 13, screw-threads into the lower end of the stem 12 and carries at its lower end a grease cup 22 of well-known construction, such, for example, as used on automobiles. A lubricant, such as a heavy grease in semi-liquid form, may thus be supplied from the grease cup 22 through the tubular connection 21 and the passage 20 to the groove 19, from which it distributes itself over the opposing bearing surfaces. Instead of the tubular connections 21 being provided with grease cups, such as at 22, they may be connected through sections of flexible hose 24 to a supply-pipe 23 which, as shown in Fig. 5, may be common to all or any desired number of the bearings. Pipe 23 may be fixed, the flexible pipe or hose connections 24 permitting relative movement of the bearings in the vibration of the shaking-section. By forcing through the supply-pipe 23 and the connections 21 and 24 water under pressure (say of 20 lbs. per square inch) it will pass upward through the passage 20 into the groove 19 and there exert an upward pressure upon the axle 10, tending to slightly

lift or float the latter in its bearing, thereby materially reducing the extent and force of the contact between the bearing surfaces, with corresponding material reduction in friction. There will be some overflow of water from the bearings, but this will be of little consequence in view of the amount of overflow water which is customary and unavoidable in the operation of paper-making machines.

What I claim is:—

1. In a paper making machine, the combination with one or more rolls, of bearings therefor, each bearing including in its structure a bearing surface member having a stem thereon, a socket member rotatably supporting the bearing surface member the stem of the latter fitting the socket of the former, a supporting part of the machine upon which said socket member is mounted and vertically adjustable to vary the elevation of the bearing member, and locking means engaging the socket member to secure the same in its adjusted position.

2. In a paper making machine, the combination with one or more rolls, of bearings therefor, each bearing including in its structure a bearing surface member having a stem thereon, and an annular surface, a socket member having an annular seat against which the annular surface on the bearing member bears to thereby rotatably support the latter the stem of one member fitting the socket of the other, a supporting part of the machine upon which said socket member is mounted and vertically adjustable to vary the elevation of the bearing member, and locking means engaging the socket member to secure the same in its adjusted position.

3. In a paper making machine, the combination with one or more rolls, of bearings therefor each bearing including in its structure a bearing surface member having a stem thereon, a socket member rotatably supporting the bearing member the stem of the latter fitting the socket of the former, a supporting part of the machine in an opening of which the socket member is rotatably and vertically adjustable to vary the elevation of the bearing member, and locking means engaging the socket member to secure the same in its adjusted position.

4. In a paper making machine, the combination with one or more rolls, of bearings therefor each bearing including in its structure a bearing surface member having a stem thereon, an exteriorly screw-threaded socket member supporting the bearing member the stem of the latter fitting the socket of the former, a supporting part of the machine having an upright screw-threaded opening engaged by the exteriorly threaded socket member whereby rotation of the latter also adjusts it vertically to vary the ele-

vation of the bearing member, and locking means engaging the socket member to secure the same in its adjusted position.

5. In a paper making machine, the combination with one or more rolls, of bearings therefor, each bearing including in its structure a bearing surface member having a stem thereon and an annular surface, an exteriorly screw-threaded socket member having an annular seat against which the annular surface on the bearing member bears to thereby rotatably support the latter the stem of one member fitting the socket of the other, a supporting part of the machine having an upright screw-threaded opening engaged by the exteriorly threaded socket member whereby rotation of the latter also adjusts it vertically to vary the elevation of the bearing surface member, and locking means engaging the socket member to secure the same in its adjusted position.

6. In a paper making machine, the combination with one or more rolls, of bearings therefor, each bearing including in its structure a bearing surface member having a stem and an annular surface about said stem and below which the stem depends, an exteriorly screw-threaded socket member the upper end of which constitutes an annular seat against which the annular surface on the bearing member bears to thereby rotatably support the latter the stem of one member fitting the socket of the other, a supporting part of the machine having an upright screw-threaded opening engaged by the exteriorly threaded socket member whereby rotation of the latter also adjusts it vertically to vary the elevation of the bearing member, and a lock-nut on the screw-threaded socket member for securing the same in its adjusted position.

7. In a paper making machine, the combination of one or more rolls, bearings therefor each including in its structure a bearing surface member having a stem thereon with a passage extending longitudinally through said stem to the bearing surface of the member, a tubular member into which said stem fits, said tubular member being adjustably positioned in an opening in a supporting part of the machine; and adapted by its adjustment to change the position of the bearing surface member and means connecting

to the outer end of the passage in the bearing surface member for supplying a fluid through said passage.

8. In a paper making machine, the combination of one or more rolls, bearings therefor each including in its structure a bearing surface member having a stem with a passage extending longitudinally through said stem to the bearing surface of the member, a tubular exteriorly screw-threaded member into which said stem fits and which is rotatably adjustable in a screw-threaded opening in a supporting part of the machine to thereby change the position of the bearing surface member; and means connecting to the outer end of the passage in the bearing surface member for supplying a fluid through said passage.

9. In a paper making machine, the combination of one or more rolls, bearings therefor each including in its structure a bearing surface member having a stem thereon with a passage extending longitudinally through said stem to the bearing surface of the member, a tubular member within which said stem fits, said tubular member being rotatably adjustably positioned in an opening in a supporting part of the machine to thereby change the position of the bearing surface member; and means connecting to the outer end of the passage in the bearing surface member for supplying a fluid through said passage at a pressure sufficient when applied between the opposing surfaces of the bearing surface member and roll to assist in sustaining the roll.

10. A bearing comprising a bearing surface member having a stem thereon with a passage extending longitudinally through said stem to the bearing surface of the member, a rotatable longitudinally adjustable tubular supporting member into which the stem of the bearing surface member fits, and means connecting to the outer end of the passage in the bearing surface member for supplying a fluid through said passage.

In testimony whereof I have signed this specification in the presence of two subscribing witnesses.
